ATTACHMENT FOR LOOMS

Filed July 2, 1929

UNITED STATES PATENT OFFICE

HENRY K. MARTIN, OF GLOUCESTER, NEW JERSEY, ASSIGNOR TO BRESLIN BROTHERS CARPET COMPANY, INC., OF GLOUCESTER, NEW JERSEY

ATTACHMENT FOR LOOMS

Application filed July 2, 1929. Serial No. 375,429.

This invention relates to an attachment for looms and has special reference to a novel mechanism which may be attached to the ordinary loom as now constituted and by means 5 of which Wilton fabrics may be woven so that the carpet design will appear on the back as well as the front thereof.

It is not broadly new, of course, to weave carpets so that the design will appear on 10 both the front and back, and mechanisms have been heretofore provided for such purposes. Such prior devices, however, have been unduly complicated in their construction and have not possessed such reliability of 15 operation as is inherent in the mechanism about to be described.

In the drawing:

Figure 1 is a longitudinal vertical sectional view through the novel mechanism; and 20 Figure 2 is a detailed plan view of certain of the elements of the mechanism.

Referring to the drawing in more detail the numeral 1 designates a portion of one of the two standards forming a part of the 25 loom, and pivotally suspended from each of these standards is an arm 2. Supported on the lower ends of the arms 2 is a guide board 3 which is perforated to receive, what are termed in the art, lingo connections and 30 which are here designated by the numeral 4 and are weighted at their lower ends as indicated by numeral 5. By means of the weights 5 the lingo connections are normally maintained in their lower positions, and likewise 35 the figuring or warp yarns associated with them are returned to the lower shed after being called up by the jacquard mechanism or after being raised by the lifter board.

The lifter or trap board is designated by 40 the numeral 6 and is provided with a number of key-hole openings 7, the narrower portions of which are formed with countersunk 45 portions 8 to normally retain the knots 9 of the lingo connections against lateral movement. This construction of the openings 7 is well known and the lifter board 6 per se differs from other lifter boards only in that the openings 7 extend transversely of the board rather than longitudinally thereof.

50 Spaced below the lifter board 6 is a lower

guide board 11 provided with openings for the passage of the lingo connections 4. This board is anchored to the conventional uprights of the loom.

The lifter board 6 is raised and lowered 55 by means of a lever 12 pivoted at 13 to the framework of the loom. This lever is caused to oscillate about its pivot by means of a cam 14, and this movement is imparted to the lifter board 6 by means of an arm 15 which 60 is in turn connected to a lever 16 pivoted at 17 to the framework of the loom. This lever 16 is connected to the lifter board 6 by means of links 18 which pass through slots 3' in guide board 3. The extent of vertical movement of the board 6 may be varied by suitable 65 adjustment of a turnbuckle 19 associated with arm 15.

As will be pointed out more fully hereinafter, the guide board 3 in the present 70 mechanism is to be moved laterally in proper sequence with the other elements of the loom, and for this purpose the lifter board 6 is provided with an upwardly extending arm 20 on which is mounted a cam plate 21. This 75 plate 21 is formed with a rounded protuberance or cam portion 22 which is adapted to cooperate with a cam roller 23 carried by the guide board 3. It will be obvious therefore that as the cam 22 rises and falls in the regular 80 operation of the mechanism the guide board 3 will first be moved to the right (Figure 1) and then will return to its normal position due to its pendulum-like suspension means. Thus a very simple and inexpensive 85 construction is provided which is necessarily maintained in proper sequence at all times with the other mechanisms of the loom.

I will now describe the operation of the present novel mechanism in its association 90 with the closely related parts of the loom.

As is well understood, the jacquard mechanism calls up or selects desired ones from a number of racks of various colored figuring yarns. In prior and well known constructions these figuring yarns after being called up to form the pile face of the carpet are returned to the lower shed to await the next periodic operation of the mechanism, hence these yarns never pass below the weft threads 95 100

or at least never in any particular sequence. According to the operation of the present improved mechanism, however, each figuring warp after being called up is dropped below the lower shed while the unselected warp 5 yarns are retained in the upper shed, thus allowing the shuttle to carry a weft thread across the top of the yarn while in lowered position. This is accomplished by means of the special mechanism herein described.

Assuming that the lifter board is in its lower position, the jacquard mechanism selects the proper figuring warp yarn and raises it to the desired position. The lifter board 6 immediately follows, carrying up the other figuring yarns not being used in the immediate design but does not raise them so high as the one called up by the jacquard mechanism. The knot 9 of the selected lingo 10 connection being withdrawn from the countersunk portion of its slot 8 is moved over into alignment with the larger opening 7 just as soon as cam 22 moves guide board 3 to the right (Figure 1). When the jacquard 15 mechanism releases this particular figuring warp therefore, it immediately drops below the lower shed in position to allow the pick to shoot a weft thread across it so that the figuring warp will appear on the back of the 20 carpet in the identical relationship that it bears to the other figuring warps on the front of the carpet. Furthermore, by thus being interlocked below the weft thread the figuring 25 warps are securely held against removal through wear and tear on the carpet.

The trap board 6 is, of course, raised and lowered periodically by cam 14 in the usual manner and further description of its operation is therefore believed unnecessary.

In those types of looms in which wire 30 jacquards are employed the lash board 30 rises and falls with the cumberboard or trap board but to a somewhat greater degree. In order, however, to produce the pattern on the back of a carpet it is necessary that the lash 35 board 30 be lowered while the cumberboard is in raised position or is traveling toward its raised position. To accomplish this movement I provide the lazy-tongs 31 which are 40 pivotally connected at 32 to a pendulum construction 33 and has its upper end 31' connected to the lash board 30. The lower section of the lazy-tongs 31 is pivoted at 34 to a lever 35 which is pivoted at 36 to the gantry 45 rails of the loom. The opposite end of lever 35 is connected to lever 16 by means of a turn-buckle 37 so that this lever, as well as lever 16, is operated through the cam 14. The pivot point 36, it will be noted, is disposed 50 at a greater distance from the main frame of the loom than the pivot point 17, thereby providing a greater throw for this lever and producing the necessary vertical movement 55 for the lash board 30.

It will be apparent, therefore, that as the

trap or cumberboard 6 is raised the lash board 70 30 is lowered and thus allows the selected figuring warp to descend to a point below the lower shed while the unselected warp yarns are retained in the upper shed by the lifter board 6.

From the foregoing description taken in connection with the accompanying drawing it will be apparent that I have devised a mechanism in the form of an attachment for conventional looms, by means of which the design of carpet is made to appear on the back thereof. It will also be apparent that the mechanism employed is extremely simple in construction and so designed as to insure 75 reliability in operation.

In accordance with the patent statutes I have described what I now believe to be the preferred form of the invention, but inasmuch as various minor details of construction may be varied without departing from the spirit of the invention it is intended that all such variations be included within the scope of the appended claims.

What I claim as new and desire to secure 80 by Letters Patent is:

1. In a loom for weaving pile fabrics, lingo 85 connections for controlling the figuring warps, a lifter board for said connections, a guide board, means for raising and lowering the lifter board, and means connected with said lifter board for imparting a lateral movement to said guide board.

2. In a loom for weaving pile fabrics, lingo 90 connections for controlling the figuring warps, a lifter board for said connections, a guide board pivotally suspended adjacent 95 said lifter board, means for raising and lowering the lifter board, and means connected with said lifter board for imparting a lateral movement to said guide board.

3. In a loom for weaving pile fabrics, lingo 100 connections for controlling the figuring warps, a lifter board for said connections, a guide board pivotally suspended adjacent 105 said lifter board, means for raising and lowering the lifter board, and a cam carried by said lifter board for imparting a lateral movement to said guide board.

4. In a loom for weaving pile fabrics, lingo 110 connections for controlling the figuring warps, a lifter board for said connections, a guide board pivotally suspended adjacent 115 said lifter board, a second guide board disposed below said lifter board and connected 120 thereto, means for raising and lowering the lifter board and its associated guide board, and a cam carried by said lifter board for imparting a lateral movement to said first-mentioned guide board.

5. In a loom for weaving pile fabrics, lingo 125 connections for controlling the figuring warps, a lifter board for said connections, said lifter board constructed and arranged to release by lateral movement such connections 130

as have been selected to form the pile, an oscillatable guide board disposed above said lifter board, a roller carried by said guide board, a cam carried by said lifter board for cooperation with said roller, and means for raising and lowering the lifter board and its associated cam.

6. In a loom for weaving pile fabrics, lingo connections for controlling the figuring warps, a lifter board for said connections, a guide board, a lash board, means for moving the lifter board and lash board toward and from each other, and means connected with the lifter board for imparting a lateral movement to said guide board.
